STAND FOR MAILBOXES

Edward J. Kusel, 2343 Ridgewood Road, Akron, Ohio

Filed July 29, 1963, Ser. No. 76,029

Term of patent 14 years

(Cl. D74—9)

FIG. 1

The side of the stand opposite that disclosed in FIGURE 2 is identical.

I claim:

The ornamental design for a stand for mailboxes, as shown and described.
